Inventor

UNITED STATES PATENT OFFICE.

FREDERICK W. RUBY, OF JACKSON, MICHIGAN, ASSIGNOR TO RUBY MANUFACTURING COMPANY, OF JACKSON, MICHIGAN.

SIGN.

1,130,844.

Specification of Letters Patent. Patented Mar. 9, 1915.

Application filed January 8, 1910, Serial No. 537,046. Renewed March 28, 1914. Serial No. 828,097.

To all whom it may concern:

Be it known that I, FREDERICK W. RUBY, a citizen of the United States, residing at the city of Jackson, county of Jackson, and 5 State of Michigan, have invented certain new and useful Improvements in Signs, of which the following is a specification.

This invention relates to improvements in wall structures for signs or portable 10 buildings.

The main objects of this invention are: First, to provide an improved construction of signs of the bill or sign board type in which the advertisements or signs can be 15 prepared in a shop and easily and quickly set up or placed upon the supporting frame. Second, to provide an improved sign in which the sign panels may be quickly changed as may be desired. Third, to provide 20 an improved sign of the sign or bill board type which is comparatively economical to produce and easily assembled, and one which is very strong and rigid when assembled. Fourth, to provide an improved 25 sign of the sign or bill board type which is made up of a plurality of panels forming different signs or advertisements, or parts of the same sign or advertisement, which when assembled has the appearance of a unitary 30 structure. Fifth, to provide an improved wall structure which is made up of a plurality of panels which can be prepared in the shop and easily and quickly set up, and a supporting frame, which, when assembled, 35 has the appearance of a unitary structure.

Further objects, and objects relating to structural details, will definitely appear from the detailed description to follow.

I accomplish the objects of my invention 40 by the devices and means described in the following specification.

The structure described constitutes one effective embodiment of my invention.

Other embodiments would be readily de- 45 vised by those skilled in the art.

The invention is clearly defined and pointed out in the claims.

A structure constituting an effective and preferred embodiment of the features of my 50 invention is clearly illustrated in the accompanying drawing, forming a part of this specification, in which:

Figure 1 is a perspective view of the structure embodying the features of my invention, the panels being shown without any sign or advertisement thereon; Fig. 2 is a detail perspective view of the frame or support for the panels; Fig. 3 is a perspective view of one of the clips for securing the panel supporting bars or rails to the post 55 or uprights of the frame; Fig. 4 is a detail plan view of the parts showing one of these clips in position; Fig. 5 is a detail perspective view showing one of the joint pieces 10; Fig. 6 is a detail view showing the connection for the braces to the supports or posts; Fig. 7 is a sectional view taken on a line corresponding to line 7—7 of Fig. 2; Fig. 8 is a detail rear perspective of one of the panels showing its structural details; Fig. 9 60 is a detail section taken on a line corresponding to line 9—9 of Fig. 1; Fig. 10 is a detail section taken on a line corresponding to line 10—10 of Fig. 1; Fig. 11 is a detail elevation showing the means for securing the 65 panels upon the supporting frame; Fig. 12 is a detail section taken on a line corresponding to line 12—12 of Fig. 11; Fig. 13 is a detail rear view of one of the panel frames; Fig. 14 is an enlarged detail per- 70 spective showing the steps of manufacture, the frame being laid upon the panel in position for the panel to be secured thereto; and Fig. 15 is a corresponding perspective showing the manner of folding the edges of the 75 panel over the frame and the arrangement of the joint pieces.

In the drawings, similar reference characters refer to similar parts throughout the several views, and the sectional views are 80 taken looking in the direction of the little arrows at the ends of the section lines.

Referring to the drawings, the panels 1 are formed of sheet metal and are provided with rectangular frames 2. These frames 85 are formed of angle iron, each frame being formed of the single piece, the ends being brought together and welded as at 3. (See Fig. 13). These frames 2 are arranged with the angles 4 inwardly. The edges 5 of the 90 panels are folded over the outer legs or arms of the frame and secured thereon. This rigidly supports the panels so that they can be handled without liability of their being 100

bent or distorted, and they are also very effectively and rigidly supported when assembled in the supporting frame. A further advantage of this method of securing the panels to the frame is that the buckle can be taken out of the panels as they are secured upon the panel frames.

The panels are provided with projecting joint pieces 6 at their top and sides. These joint pieces are angle shaped in cross section, as is clearly illustrated in the drawing, and arranged over the infolded edges of the panels with their angles in the angles of the panel frames, their rearwardly projecting arms being riveted to the rearwardly projecting arms of the frame and their outwardly projecting arms being riveted to the outwardly projecting arms of the frame, the rivets serving to secure the panels securely upon the frame. The rivets are shown at 7 in Fig. 8.

The supporting frame consists of uprights 8 formed of angle iron and horizontally disposed supporting members or stringers 9, also formed of angle iron. When these supporting members 9 are made of pieces or sections they are connected by channel shaped joint pieces 10, (see Fig. 5) the ends of the pieces or sections being brought together to form a butt joint and the joint pieces being secured thereon by means of bolts 11. (See Fig. 5).

The horizontal and upright pieces are connected by means of the clips 12 which have pairs of oppositely disposed lug-like ears 13 forming channels to receive the members to be connected. These coupling or clip members 12 avoid the necessity of brace pieces for the members 8 and 9.

40 The members 8 and 9 are connected by means of the bolts 14 arranged therethrough and through the coupling or clip members 12. (See Fig. 4).

45 The frame is supported by props or braces 15 arranged at a suitable angle.

The uprights and the braces are mounted on suitable bases 16 having foot portions 17 on their lower ends which makes them more rigid when set.

50 The bases are provided with longitudinal slots 18 adjusted to receive the bolts 19 so that the uprights and their braces can be readily adjusted for the leveling of the supporting frame without regard to the setting of the bases.

The braces or props 15 are formed of angle iron, one arm of the angle iron being extended upwardly into an attaching strap 20 through which the attaching bolts 21 are arranged, as clearly appears in Fig. 6. This provides a simple and effective supporting frame.

To provide a means for quickly and securely attaching the panels to the supporting frame, I form support engaging mem-

bers, or fasteners, on the panel frames by means of slots 22 in the edges of the rearwardly projecting arms of the frames. These slots 22 are bayonet slots, as shown, and are adapted to receive the forwardly projecting arms of the supporting members 9. These supporting members are provided with retainers 23, the retainers being angle pieces secured to the supporting members, forming flange-like projections thereon. (See Figs. 2 and 7).

In placing the panels they are slipped upon the forwardly projecting arms of the supporting members 9 and moved along thereon until the attaching members of the panels are engaged with the retaining members of the supports.

To retain the panels upon their supports I provide hook-like securing members 24 which are adapted to be engaged in the holes 25 in the members 9. These holes are spaced so that any desired panel may be secured, although in practice it is only necessary to secure the end panels.

When the panels are erected upon the frame they form in effect a continuous sign or board.

The joint strips are arranged to interlap, as clearly appears in Figs. 9 and 10, so that tight joints are formed between the panels which assists in securing them in place and prevents their buckling or otherwise getting out of alignment.

My improved sign when completed has the appearance of a unitary structure. The several panels are adapted to receive parts of a single advertisement, or each panel may contain a single advertisement.

Advertisements can be placed upon the panels either in the form of bills, posters or the like, or they may be painted directly upon the panel. This work can be done in the shop and the panels set up or placed upon the supporting frame, as desired. The advantage of this will be obvious, as the fresh work is not exposed to the weather as it can be done in the shop, where all conveniences may be had for the workmen, and shipped or carted to the place of display where the sign can be readily and quickly assembled, the panels being changed as desired in modifying or changing the sign.

When the work is to be done on the ground where the sign is to be set up, panels can be placed in the lower supports which form an effective holder therefor while the workman is at work thereon.

I have illustrated and described my improved sign in the form preferred by me, as it is the form in which it has been embodied and in which it is in use at the present time. I am, however, aware that it is capable of considerable variation in structural details without departing from my invention, and I desire to be understood as

claiming the same specifically in the form illustrated, as well as broadly within the scope of the appended claims.

Having thus described my invention, what I claim as new and desire to secure by Letters Patent is:

1. In a sign, the combination with a plurality of panels formed of sheet metal; frames for said panels formed of L-shaped angle iron, arranged on the sides of the panels with the angles inwardly with one arm projecting rearwardly; projecting joint pieces on the top and sides of said panels, said joint pieces being L-shaped in cross section and arranged in the angles of the panel frames over the infolded edges of the panels, the arms of the joint pieces being secured to the corresponding arms of the panel frames, the meeting joint pieces being adapted to interlap when the panels are arranged edge to edge to close the joint between the panels and support the panels in alinement.
2. In a sign, the combination with a plurality of panels formed of sheet metal; frames for said panels formed of L-shaped angle iron arranged with one of the arms projecting rearwardly, the rearwardly projecting arms of the frame irons having slots therein to provide support engaging members; supports for said panels having flange-like engaging members adapted to be engaged in said slots in said panel frames whereby said panels are detachably supported on said supports; and hook-like retainers on said panels, said supports being provided with holes suitably spaced to receive said retainers.
3. In a sign, the combination with a plurality of panels formed of sheet metal; frames for said panels formed of L-shaped angle iron arranged with one of the arms projecting rearwardly, the rearwardly projecting arms of the frame irons having bayonet slots therein to provide support engaging members; angle iron supporting members for said panels arranged with one of their arms projecting forwardly and flange-like panel engaging members secured on the forwardly projecting arms of said supporting members to engage said slots in said panel frames; and hook-like retainers on said panels, said supporting members being provided with holes suitably spaced to receive said retainers.
4. In a sign, the combination with a plurality of panels formed of sheet metal; frames for said panels formed of L-shaped angle iron arranged with one of the arms projecting rearwardly, the rearwardly projecting arms of the frame irons having slots therein to provide support engaging members; angle iron supporting members for said panels arranged with one of their arms projecting forwardly, to engage said slots in said panel frames; and hook-like retainers

on said panels, said supporting members being provided with holes suitably spaced to receive said retainers.

5. In a sign, the combination with a plurality of panels formed of sheet metal; frames for said panels formed of L-shaped angle iron, arranged with the angles outwardly; projecting joint strips for said panels, said joint strips being angle shaped in cross section and arranged in the angles of the panel frames, the arms of the joint pieces being secured to the corresponding arms of the panel frames, the meeting joint pieces being adapted to overlap when the panels are arranged edge to edge to close the joint between the panels and support the panels in alinement.

6. In a sign, the combination with a plurality of panels formed of sheet metal; frames for said panels formed of L-shaped angle iron arranged with one of the arms projecting rearwardly, the rearwardly projecting arms of the frame irons having support engaging members thereon; projecting joint strips for said panels, the meeting edges thereof being adapted to overlap when the panels are arranged edge to edge to close the joint between the panels and support the panels in alinement; and supports for said panels having engaging members adapted to co-act with said engaging members of said panels.

7. In a sign, the combination of a plurality of sheet metal panels; frames for said panels having attaching members thereon; and a supporting frame comprising horizontally-disposed supporting bars, said attaching members being adapted to be engaged with and moved longitudinally upon said supporting bars, said supporting bars being provided with coacting engaging members with which said attaching members of said panels may be engaged by such longitudinal movement.

8. In a wall structure, the combination with a plurality of sheet metal panels, of frames for said panels formed of angle iron provided with rearwardly projecting arms, said rearwardly projecting arms being provided with bayonet slots, supports for said panels comprising horizontally disposed supporting bars provided with flanges adapted to engage in said bayonet slots whereby said panel frames are held from movement except longitudinally of said horizontally disposed supporting bars, and retaining bolts connecting said horizontally disposed supporting bars and said panel frames and preventing the latter from longitudinal movement on the former, all co-acting substantially as described for the purpose specified.

9. In a wall structure, the combination with a plurality of sheet metal panels, of frames for said panels formed of angle iron.

supports for said panels comprising a plurality of horizontally disposed supporting bars, said panel frames being movable longitudinally of said supporting bars and adapted to engage therewith whereby all movement of said frame relative to said bars except longitudinally thereof is prevented, and retaining bolts extending longitudinally of said bars and connecting said supporting bars and said panel frames whereby said frames are held against longitudinal move-

ment upon said supporting bars, all coacting substantially as described for the purpose specified.

In witness whereof, I have hereunto set 15 my hand and seal in the presence of two witnesses.
